Original application September 19, 1936, Serial
No. 101,630. Divided and this application
July 8, 1937, Serial No. 152,553

4 Claims. (Cl. 139—217)

This invention pertains to weaving shuttles and relates more particularly to improved guiding and tensioning means for a shuttle of the self-threading type, the present application being a division of copending application for Letters Patent, Serial No. 101,630, filed September 19, 1936. Uniformity of yarn tension is a very important desideratum for perfect weaving, but has been very difficult of attainment, at least without serious interference with easy and automatic threading, and particularly when weaving wiry yarn or yarn which readily strands or separates into a plurality of filaments, both of which characteristics are common to yarns of the cellulose derivative type, for example, the yarn commonly known as "rayon".

A further difficulty experienced in weaving wiry or hard-twisted yarn by the use of a self-threading shuttle results from the tendency of such yarn to kink adjacent to the delivery eye of the shuttle, and in so kinking to twist and writhe in such a way as to escape from the shuttle eye.

Principal objects of the present invention are to provide self-threading tensioning and guiding means capable of exerting a substantially uniform and predetermined tension upon the yarn during both forward and reverse picks of the shuttle; to provide ready and accurate means for adjusting the degree of tension imposed upon the yarn and for maintaining the selected tension indefinitely; to provide the tension means such that easy and certain self-threading is assured; to provide a delivery eye and associated parts such as to insure accurate entry of the yarn into the delivery grooves in the outer surfaces of the shuttle; to provide a wear-resistant delivery eye readily capable of replacement if broken or worn; and to provide improved means for securing the yarn guiding and tensioning block in the shuttle body without danger of affecting the predetermined yarn tension.

Other objects and advantages of the invention will be made manifest in the following more detailed description and by reference to the accompanying drawing, wherein:

Fig. 1 is a fragmentary front side elevation of a weaving shuttle equipped with the improved guiding and tensioning means,—the shuttle being viewed from the side at which the delivery eye is located;

Fig. 2 is a fragmentary plan view of the parts shown in Fig. 1;

Fig. 3 is a plan view of the improved yarn guide block removed from the shuttle body;

Fig. 4 is a side elevation of the block shown in Fig. 3;

Fig. 5 is an elevation of the tensioning block viewed from its forward end;

Fig. 6 is a fragmentary plan view substantially 5 on the line 6—6 of Fig. 5 and indicating the path of the yarn in broken lines;

Fig. 7 is a fragmentary section on the line 7—7 of Fig. 4;

Fig. 8 is a section, to larger scale, on the line 10 8—8 of Fig. 4;

Figs. 9, 10 and 11 are fragmentary side elevations of the tensioning block, to substantially the same scale as Fig. 8, illustrating various improved means for maintaining the adjustment of 15 the tension;

Fig. 12 is an end elevation of the tensioning screw of the device of Fig. 11;

Fig. 13 is an end elevation illustrating the tensioning screw of the device of Figs. 9 and 10. 20

Fig. 14 is a side elevation of the yarn guide eye piece removed from the guide block;

Fig. 15 is a fragmentary horizontal section on the line 15—15 of Fig. 4; and

Fig. 16 is a fragmentary section through the 25 shuttle, substantially on the line 16—16 of Fig. 1.

Referring to the drawing, the numeral 1 designates a weaving shuttle, of the type commonly used in automatic looms, provided at its front end with a metal tip 2 in the usual way. The shuttle body is provided with a chamber 3 (Fig. 2) for the reception of the bobbin 4,—such chamber having a forward extension 5 for the reception of the thread guide block 6. This block may be of metal or any other suitable material commonly 30 employed for the purpose,—the present invention being particularly concerned with improvements in this block and associated parts. 35

The front face 7 of the shuttle body is provided with the usual longitudinally extending 40 shallow thread groove 8 (Fig. 1), having a forward extension comprising the parts 9 and 9^a, said extension of the groove intersecting a laterally directed portion 5^a of the chamber 5.

The block 6 has a substantially flat bottom surface 10 which normally seats upon the floor of the chamber 5 of the shuttle body, such block having the spaced side walls 11 and 12 (Fig. 8) between which is a longitudinally extending portion 13 of the yarn guide passage. Near the entrance 50 end of this passage a transverse pin or stud 14 extends from one wall to the other of the block. Preferably this stud or pin is provided with an externally screw-threaded head 15 which engages a threaded bore in the side wall of the block (Fig. 55

8). This pin or stud 14 forms a support for a pair of tension plates 16 and 17 respectively, which are disposed face to face in a substantially vertical position, similarly to the tension plates disclosed in the patent to Comisky No. 1,387,837, dated May 24, 1921, for example, said tension plates having openings through which the stud 14 passes loosely. The upper ends of the plates 16 and 17 are bent outwardly substantially at right angles to the body portions of these plates, as shown at 16^a for example, and the outer end portions of these parts 16^a are furnished with downwardly directed wings 16^b forming guide elements. These guide elements are arranged to 10 slide loosely in wear-resistant bushings 17^a in openings in the side walls 11 and 12, respectively, of the block. The tension plates are thus free to move toward and from each other but at the same time are prevented from tilting excessively. 15

20 A coiled compression spring 19 bears against the left-hand surface (Fig. 8) of the plate 16, its outer end bearing against a screw-threaded stud 20 received in an opening in the wall 11 of the block. Preferably the spring 19 bears against 25 the plate 16 at a point about midway of the height of the latter, preferably slightly below where the projected axis of the bobbin would intersect the plate. A similar spring 21 bears against the right-hand or outer face of the plate 30 17 at a point opposite to the spring 19. The outer end of the spring 21 is received in an axial pocket in a screw-threaded stud 22 engaging a screw-threaded opening in the wall 12 of the block. Preferably this stud 22 is provided with a polygonal socket 23 for the reception of a wrench by 35 means of which it may be turned, thereby to vary the resilient pressure exerted by the spring 21 against the plate 17, so as to adjust the tension upon the yarn which passes between the tension plates. 40

Preferably means is provided to retain the adjusting stud 22 in place after it has once been adjusted, so that the tension will not accidentally vary during the operation of the shuttle, in 45 spite of the violent shocks to which the shuttle is subjected. For this purpose, as illustrated in Figs. 10 and 13, the screw-threaded peripheral surface of the stud 22 may be provided with flat surfaces or facets 24, preferably disposed symmetrically, as shown in Fig. 13. In the arrangement shown in Fig. 10, a flat bow spring 24^a is disposed within a horizontal bore 25 in the thickness of the wall 12 of the block, said bore intersecting the threaded opening which receives the 50 stud 22, so that the central portion of the spring 24^a resiliently bears upon the peripheral surface of the stud,—normally contacting one of the facets 24 and thus holding the stud in adjusted position, although permitting it to be turned 55 when sufficient force is applied by means of a wrench. 60

In Fig. 9 a slight modification is illustrated, wherein the spring 24^a, instead of being mounted in a bore in the block, is arranged in a horizontal 65 slot or recess 25^a in the outer surface of the wall 12 of the block.

A further modification of the tension-retaining means is illustrated in Figs. 11 and 12. In this instance the stud 22^a is furnished with 70 spaced peripheral V notches 24^b, while the block is provided with a spring 26 seated in a recess 27 in the rear edge of the wall 12, the spring being fixed in position at its lower end and having a tooth member 28 at its upper end which 75 may engage any one of the notches 24^b of the

stud, thereby to hold the stud in adjusted position.

The block is furnished with a substantially horizontal guide pin 29 (Fig. 6) in the longitudinal portion 13 of the yarn passage and preferably at a point just forward of the tension plates 16 and 17, the pin 29 being at such an elevation that the projected axis of the bobbin lies substantially tangent to its upper surface. The block is also furnished with a substantially vertical guide pin 30, which defines the junction between the longitudinal portion 13 of the thread passage and a transverse portion of said passage which leads to the thread delivery eye. The pins 29 and 30 may be of porcelain or any other suitable wear-resistant material.

The block 6 has a lateral extension 6^a which is disposed in the extension 5^a of the chamber 5, such extension 6^a having an outer vertical face 6^b which is substantially flush with the forward 20 face 7 of the shuttle body. This extension is furnished with a horizontal channel 31, whose upper and lower walls are substantially aligned with the corresponding walls of the groove 9, 9^a of the shuttle body. The extension 6^a is provided with a vertical socket S (Fig. 15) which intersects the upper and lower walls of the channel 31, and which is designed to receive an eyepiece 32 (Fig. 7). This eyepiece (Fig. 14) may be of porcelain, hardened alloy steel, nitrided 30 steel, or the like, of a wear-resistant character, and has the yarn delivery eye 33, the axis of which is perpendicular to the axis of the shuttle and substantially tangent to that point of the guide post 30 at which the yarn Y leaves said 35 post on its way to the delivery eye. The eyepiece 32 has a lower surface 34 (Fig. 14) which normally rests against the floor of the chamber 5 of the shuttle when the block 6 is positioned within the chamber 5. However, the eyepiece 32 is freely removable from the block 6 when the latter is removed from the shuttle, and thus the eyepiece may readily be replaced if worn or broken, or if it be desired to substitute a block of different 40 material or one having a delivery eye of different 45 size or shape.

The eyepiece is furnished with a substantially vertical threading slot 35 at its lower part, one side of said slot being defined by the curved horn-like portion 36 of the eyepiece, such horn-like portion having an outer curved guiding face 37. The parts are so dimensioned that when the eyepiece is disposed in the socket in the block, the tip of the horn 36 is disposed below the lower wall 38 of the channel 31 (Fig. 4). As 50 illustrated in Fig. 15, that part of the socket S which intersects the lower wall 38 of channel 31 receives the eyepiece, is beveled and widened at its forward end, as indicated at 39 in Fig. 15, so as to form a yarn-receiving clearance between 55 the wall of the socket and the tip of horn 36, thereby to permit the yarn, in following the curved surface 37, to snap beneath the tip of the horn and then to move up through the slot 60 35 into the eye 33. However, it will be noted 65 that when the thread has once entered the eye 33, it is substantially impossible for it to escape from said eye by moving in a downward direction, since the lower wall surface 38 of the channel 31 lies above the tip of the horn, and since 70 there is no guide surface leading from the eye 33 which would assist the yarn in moving downwardly and out from beneath the tip of the horn. Thus no matter how much the yarn may 75 kink or writhe during the operation of the 75

shuttle, it is substantially impossible for it to escape from the shuttle eye, although, in threading, the yarn easily enters the eye.

The block 6 is provided with the usual forwardly directed guard member 40 and with the beak 41 having the narrow tip 42 which underlies the guard 40. The under surface of the beak 41 is smoothly finished and extends downwardly and laterally from the tip 42 toward the curved guide surface 37 of the eyepiece 32. As illustrated, this beak 41 is wholly devoid of any downwardly directed projections, horns or other elements to impede the yarn in its downward and lateral movement.

In threading, during the first pick of the shuttle, which is to the left, as viewed in Figs. 1 and 2, the yarn being held at its free extremity is drawn downwardly into the longitudinal portion 13 of the thread passage, it being noted that this slot is freely open throughout its length, and that the surfaces 44 and 45 at the opposite sides of this slot are smoothly sloped so as to guide the yarn toward the open entrance to the passage as it is drawn taut lengthwise of the shuttle. It may further be noted that the entrance of the yarn between the tension plates 16 and 17 is facilitated by the outward curvature of these plates where they merge with the parts 16^a so that upon this first pick the yarn is with certainty laid into the longitudinal portion of the passage and enters between the tension plates, where it is supported by the guide pin 29. Normally, near the end of this pick, the yarn snaps down beneath the guard 40 and under the tip 42 of the beak 41. Upon the second pick, when the shuttle moves to the right (as viewed in Figs. 1 and 2) the yarn swings laterally and slides easily down along the under surface 43 of the beak, and, meeting no obstruction whatever, quickly contacts with the outer curved surface of the horn 37 and is guided by the latter so as to pass the tip of the horn and enter the slot 35 and the eye 33, being now drawn around the post 30.

Since the axis of the guide eye 33 is substantially tangent to that point of the post 30 at which the yarn leaves the latter, and is also perpendicular to the axis of the shuttle, and since the axis of the guide eye 33 is also substantially midway between the upper and lower walls of the channel 31, it is evident that as the shuttle is picked back and forth, the yarn which emerges from the guide eye leads away from the shuttle at the same angle whether the shuttle be moving in one direction or the other. Thus the tension devices are subjected to substantially the same resistance to movement of the yarn, whether the shuttle be moving in one direction or the other, and thus it is possible to obtain a more constant tension and more even weaving than is usually the case.

In order to hold the block 6 in position, but without affecting the tension after the latter has once been adjusted, it is preferred to employ the arrangement illustrated in Fig. 16. As thus shown, the block 6 is furnished with a transverse screw-threaded opening for the reception of the screw-threaded shank portion 46 of a retaining screw having a screw-threaded head portion 47 of larger diameter than the shank portion 46 but preferably threaded with the same pitch thread as the latter. This threaded head portion 47 engages a screw-threaded bore in the body 1 of the shuttle, but the opposite end 48 of the screw freely enters an unthreaded bore of the shuttle

body. The screw is of a length less than the thickness of the shuttle so that the screw does not project through to the forward face of the shuttle. With this arrangement, no matter how hard the screw may be set up, it does not tend to draw together the side walls of the shuttle body and thereby pinch the guide block so as to change the setting of the tension devices carried by the latter. It has been found that in prior constructions, where the screw for holding the block in position extends all of the way through the shuttle body, and is provided with means such as a nut, for tightening it, the wood of the shuttle is so squeezed against the guide block as to change the setting of the tension. The present invention avoids any such action.

With my arrangement it is thus possible to adjust the tension very delicately, as by means of the screw-threaded stud 22, with the assurance that the tension thus once set will not be varied either by reason of the sharp blows and shocks to which the shuttle is subjected during use, or by any manipulations necessary for fixing the block within the shuttle body. It should further be noted that since the screw which holds the block in position does not extend through the forward face of the shuttle, the latter is left smooth and unbroken and there is no danger that the yarn will be caught or abraded by contact with the end of the screw or by rubbing across the end of an open bore in the shuttle body.

In practice it has been found that the improved guide block with its associated parts permits yarn to be entered into the delivery eye with the greatest ease and certainty so that proper threading of the shuttle is substantially assured after the second pick. It has further been found that with this arrangement rayon or similar yarns of a very slippery and wiry nature, may readily be woven and the tension maintained very accurately even without recourse to the full tension which has commonly been thought necessary to use in weaving yarns of this character. It has further been found that even in weaving such wiry yarns as those above noted and which tend to kink and writhe in the shuttle eye, there is substantially no possibility of unthreading of the shuttle accidentally by reason of such action of the yarn, while, as above noted, the symmetrical delivery of the yarn to and from the shuttle eye assists in maintaining a uniform tension. Moreover, the eyepiece may easily be removed and replaced when desired merely by removing the block from the shuttle body,—permitting the eye to drop from the block, and then reinserting the new eye from the bottom of the block, all without the necessity of using tools or special instruments designed for the purpose.

While certain desirable embodiments of the invention have been illustrated by way of example, it is to be understood that the invention is not necessarily limited thereto, but that all equivalents are to be regarded as falling within the purview of the invention as set forth in the appended claims.

I claim:

1. A yarn guide block of the kind which in use is seated within a chamber in a shuttle body with its vertical walls engaging the walls of the chamber, and which has therein yarn tension means, including a tensioning spring and a screw which engages a threaded bore in the block and by means of which the pressure exerted by the spring may be varied, and having detent means

- which engages the periphery of the screw, thereby always to oppose turning of the screw but which allows the screw to be turned when sufficient force is applied, characterized in that the 5 block has a detent receiving cavity within its substance and so located as to be closed and concealed by the wall of the shuttle chamber when the block is in operative position in the chamber, the detent being disposed within said cavity and wholly within the substance of the block.
- 10 2. In a yarn guiding block of the kind which in use is seated within a chamber in a shuttle body with its vertical walls in contact with the walls of the chamber, and which has yarn tension 15 means comprising a pair of relatively movable yarn tension plates, a spring for yieldingly urging one of said plates toward the other, a screw for varying the pressure exerted by the spring, the screw engaging a threaded bore in the block, and 20 20 detent means operative to oppose turning of the screw but which allows the screw to be turned in either direction when sufficient force is applied, characterized in that the block has a detent receiving cavity which opens at the outer vertical 25 25 surface of the block at a point such that the entrance to the cavity is closed by the wall of the bobbin chamber when the block is operatively seated in said chamber, and in that the detent means consists of a single resilient part.
- 30 3. A yarn guide block of the kind which when in use is seated within a chamber in a shuttle body with its vertical walls substantially in contact with the walls of the chamber, and which has therein yarn tension means including a tensioning spring and a screw which engages a 35

threaded bore in the block for varying the pressure exerted by the spring, and having detent means which engages the periphery of the screw, thereby at all times to oppose turning of the screw, but which allows the screw to be turned when sufficient force is applied, characterized in that the block has a detent receiving cavity which opens at a rearwardly directed surface of the block, such surface abutting a wall of the chamber in the shuttle body when the block is 10 seated in said chamber, the entrance to said cavity in the block being concealed when the block is in operative position, the detent means consisting of a single unitary resilient element wholly disposed within said cavity. 15

4. A yarn guide block of the kind which when in use is seated within a chamber in a shuttle body with its vertical walls substantially in contact with the walls of the chamber, and which has therein yarn tension means comprising a 20 pair of relatively movable yarn tension plates, a spring for yieldingly urging one of said plates toward the other, a screw for varying the pressure exerted by the spring, said screw engaging a threaded bore in the block, characterized in that the block has a detent receiving cavity which opens at one of the vertical surfaces of the 25 block which abuts a wall of the chamber in the shuttle when the block is seated therein, whereby the entrance to said cavity is closed by the wall 30 of the chamber, the detent being a bowed spring having its central portion so disposed as resiliently to engage the periphery of the screw.
